US00D871291S

(12) **United States Design Patent** (10) Patent No.: **US D871,291 S**
(45) Date of Patent: **** Dec. 31, 2019**

(54) **DOOR HANDLE FOR VEHICLES**

(71) Applicant: **JUNGHEINRICH AKTIENGESELLSCHAFT**, Hamburg (DE)

(72) Inventor: **Michael Niebuh**, Bargteheide (DE)

(73) Assignee: **Jungheinrich Aktiengesellschaft** (DE)

(**) Term: **15 Years**

(21) Appl. No.: **35/506,097**

(22) Filed: **Jul. 23, 2018**

(80) **Hague Agreement Data**

Int. Filing Date: **Jul. 23, 2018**

Int. Reg. No.: **DM/103685**

Int. Reg. Date: **Jul. 23, 2018**

Int. Reg. Pub. Date: **Nov. 23, 2018**

(30) **Foreign Application Priority Data**

Jan. 24, 2018 (EM) 001464911-0001

(51) LOC (12) Cl. **12-16**

(52) U.S. Cl.

USPC **D12/195; D12/196**

(58) **Field of Classification Search**

USPC D12/400, 195-196; D8/300, 315, 320; D6/204

CPC B60R 13/0243

See application file for complete search history.
